bit end of the screwdriver unencumbered for normal use.

I claim:

1. In combination with a screwdriver having a handle, shank and screw engaging bit; a screw holding attachment, comprising; means concentrically mounting a screw gripping jaw assembly on said shank for axial and radial movement relative thereto; said jaw assembly having a screw head engaging end remote from said handle; first biasing means for biasing said jaw assembly axially in the direction of said handle and radially expanding said screw head engaging end; and said first named means including cam means engaging the outer periphery of said jaw assembly and second biasing means biasing said cam means axially in the direction of said handle for radially contracting the screw head engaging end thereof, whereby manual movement of said cam means in opposition to said second biasing means permits expansion of the screw head engaging end of said jaw assembly under the influence of said first biasing means for the position of a screw head on said bit in position to be gripped by said jaw assembly upon release of said cam means.

2. The combination of claim 1 wherein said first biasing means includes two distinct springs.

3. The combination of claim 2 wherein said second biasing means includes a single spring.

4. The combination of claim 3 wherein said first

named means further includes jaw anchor means positioned intermediate said cam means and said handle; said jaw assembly including a plurality of jaws having engaging fulcral surfaces intermediate said cam means and jaw anchor; each said jaw including an integral extension projecting through an oversize opening in said jaw anchor in the direction of said handle; and one of said spring means of said first biasing means engaging each said jaw extension on the handle side of said jaw anchor.

5. The combination of claim 4 wherein said single spring is a tension spring interconnecting said jaw anchor and cam means.

6. The combination of claim 4 wherein the outer surfaces of said jaws are generally convergent in the direction of the bit end of said shank; and said cam means includes an arcuate opening telescoped over said jaws whereby said single spring biases said cam means in the direction of said jaw anchor for contracting the screw head engaging end of said jaw assembly.

7. The combination of claim 6 wherein the inner and outer surfaces of said jaws are substantially parallel; and each said jaw includes a plurality of screw head engaging recesses axially spaced along the inner screw engaging surfaces thereof whereby screw heads of varying diameters may be positively anchored against movement relative to said bit.

Primary Examiner—Donald R. Schran**Assistant Examiner**—James F. Coan**Attorney**—Robert K. Rhea[57] **ABSTRACT**

A pair of motor driven circular saws are mounted on opposite sides of a frame supported horizontal barrel stave carrying conveyor with the axes of the saws perpendicular to the direction of conveyor travel and their planes arranged in downwardly converging relation. Spring loaded guide rollers, forming a part of the saw driving motor supports, adjusts the position of the saws in a desired barrel stave edge trimming spaced-apart relation by contact with the respective opposing longitudinal sides of a barrel stave to be trimmed as it is moved by the conveyor between the saws.

Lock means actuated by spring loaded pressure rollers overlying the position of the barrel stave when moved by the conveyor maintains the adjusted spaced-apart relation of the saws for the duration of the saw trimming action on each side of each stave moved through the machine by the conveyor.
